O. NADOLNEY

HINGE

Filed May 9, 1922

Inventor

Otto Nadolney,

Assignee

Attorney

UNITED STATES PATENT OFFICE.

OTTO NADOLNEY, OF NANTICOKE, PENNSYLVANIA.

HINGE.

Application filed May 9, 1922. Serial No. 559,526.

To all whom it may concern:

Be it known that I, OTTO NADOLNEY, a citizen of the United States of America, and resident of Nanticoke, in the county of 5 Luzerne and State of Pennsylvania, have invented certain new and useful Improvements in Hinges, of which the following is a specification.

This invention relates to hinges, and particularly to hinges having special reference for use on screen doors and the like, the said invention including novel means whereby the mounting for a screen door may be permanently set on a door frame to support the 10 hinges of the door, yet permitting the removal of the hinges when the door is to be taken down, a provision which obviates the necessity for placing and removing screws when the door is again to be hung or taken 15 down.

It is well known that when screws are removed from the hinge leaves or butts, season after season, the anchorages for the screws become impaired and the screw holes 20 must be plugged or larger screws employed, and other disadvantages result. By the use 25 of the invention forming the subject of this application, screen doors may be hung or removed without impairing the door frame, as stated, and furthermore the work of applying or removing the door may be expeditiously accomplished.

It is a further object of this invention to provide a door hinge mounting of the 30 character indicated, including means for permitting the door to be hung within the opening in the frame, or to close the opening in the frame by bearing against the side of the frame, so that by a simple expedient, the mounting for the door may be attached 35 to the frame to permit the door to be hung in either of the positions indicated.

A further object of this invention is to produce a device of the character indicated 40 which can be readily changed to operate in either manner herein set forth, and without materially increasing the cost of the equipment necessary to effect the result.

With the foregoing and other objects in view, the invention consists in the details 45 of construction, and in the arrangement and combination of parts to be hereinafter more fully set forth and claimed.

In describing the invention in detail, 50 reference will be had to the accompanying drawings forming part of this application,

wherein like characters denote corresponding parts in the several views, and in which—

Figure 1 illustrates a view in perspective 60 of a door hinge and a mounting therefor embodying the invention;

Figure 2 illustrates a perspective view of one of the mountings;

Figure 3 illustrates a perspective view of 65 an attachment therefor to secure the mounting clear of the side of the door frame;

Figure 4 illustrates a sectional view of the mounting and the attachment for anchoring 70 the same;

Figure 5 illustrates a sectional view of a 75 fragment of a door frame and door showing the hinge applied thereto; and

Figure 6 illustrates a similar view showing the relation of the mounting disclosed 80 in Fig. 4 applied to the frame and door.

In these drawings 10 denotes one of the hinge leaves and 11 the coacting leaf, which are mounted on a pintle or pivot 12, associated with a spring 13, by which the door 85 is operated to close it.

The hinge leaves have base elements or plates and outstanding ears that extend beyond the edges of the plates on a line between the adjacent edges of the said bases 90 to receive the pivot, and when these devices are applied to a door and its frame with the bases of the leaves applied to the outer surface of the door or frame, there is a clearance of an appreciable 95 degree between the inner edges of the ears and the said door or frame to receive the bases, and the ears can then be moved closer to the door or frame without changing the construction of the hinge.

The edges of the leaves converge toward their bottoms in order that when they are fitted to the socket or mounting, they will be supported therein, as will presently appear.

Each mounting, in the present embodiment of the invention, comprises a plate 14 provided with apertures 15 to receive screws by which the mountings are attached to the door frame. The plate 14 has its edges shaped to form guides 16 and 17 in which one of the leaves of the hinge is slidable and by which the hinge is supported. The edges of the plate 14 converge toward the bottom, and therefore, as the leaf is slidable between the flanges and the plate, they bind or bear against the walls or surfaces of the 105 110

flanges, which flanges associated with the plate, might be said to constitute a socket to receive a leaf.

As shown in Fig. 5, the leaves of the 5 hinges are employed in association with a door that is hung within a frame, and in this employment of the invention, the mounting is permanently applied to the frame and the hinge is removably secured in the mounting, it being possible to remove the hinge 10 from the mounting by lifting the door.

In event of it being necessary or desirable 15 to mount the door with its side bearing against the door frame in order to close the opening in the door frame, the equipment 20 would consist substantially of the elements shown in Figs. 4 and 6, wherein the mounting 14 is the same as heretofore described, but instead of having screws applied to the 25 holes 15 for anchoring the mounting directly to the door frame, brackets 18 are interposed between the mounting and the door frame and act as supports for the mounting. Each 30 bracket has two apertured flanges 19 and 20, one of which is secured to the door frame by fastenings 21 such as screws, whereas the other flange is connected to the mounting by fastenings such as screw bolts 22. The brackets are of such height as to correspond 35 approximately to the width of the door with which they are to be used, although these proportions may be varied within predetermined bounds without affecting the operation of the device. When the brackets have been applied to the door frame and the mountings are attached to the said brackets, the door may be hung or removed

in the same way as it is hung or removed with the equipment shown in Fig. 5, but it will be seen that advantage results from providing means which hold the socket or mounting in spaced relation to the door frame, when the door is to be hung outside of the opening in the door frame.

By the simple expedients illustrated and 45 described, provision is made for ranges of adjustment and increased utility of a hanging for screen doors or the like, as will be understood by those skilled in the art.

The hinge and bracket may be made suitable for any size door.

I claim:

In a door mounting, brackets having apertured flanges, the said brackets being of a height to compensate for the difference in thickness of doors, one of said apertured flanges of each bracket being adapted to be secured to a door frame, a plate provided with apertures by which the said plate may be secured to a door frame or to the said brackets, fastenings extending through the said apertures for anchoring the plate on a door frame in operative relation to a door, the said plate having its edges converging downwardly and inturned to form guides, and a hinge having two leaves, one of which may be secured to a door and the other of which tapers to the configuration of the space between the guides of the plate, the said last mentioned leaf being of a thickness to fit 60 in the guides formed by the plate and its flanges, as and for the purpose described.

OTTO NADOLNEY.
